SWITCH STAND

Filed Feb. 19, 1926

2 Sheets-Sheet 2

UNITED STATES PATENT OFFICE.

JAMES M. HOFFER, OF STEELTON, PENNSYLVANIA, ASSIGNOR TO BETHLEHEM STEEL COMPANY.

SWITCH STAND.

Application filed February 19, 1926. Serial No. 89,262.

My invention relates to switch stands of the spring type, that is, to that type which permits of a train trailing through the switch, spring devices being employed in order that a switch point may move away from a rail due to passage of wheel flanges therebetween, and my invention has for an object to provide a switch stand of this character which shall function as a spring switch stand only in limiting of final positions and as a positive switch stand in all other positions.

A further object of my invention is to provide a spring switch stand having such an arrangement of parts that the spring devices do not oppose manual operation of the switch.

It has heretofore been common practice to lock the operating lever of a spring switch stand to a member of the yieldable mechanism. An objection to such an arrangement is that one may, with a suitable implement, throw the switch. It is, therefore, a further object of my invention to provide a spring switch stand of such a character that the lever may be locked to a stationary part of the structure.

A further object of my invention is to provide a spring switch stand which shall be readily convertible into one of the positive type.

A further object of my invention is to provide a spring switch stand of the gearless type wherein the mechanism for transmitting motion from the switch operating lever to the spindle shall transmit motion with the greatest mechanical advantage at the beginning and at the end of movements of the switch lever.

Apparatus made in accordance with my invention is illustrated in the accompanying drawings, forming a part of this application in which—

Fig. 1 is a side elevation of my improved type of switch stand;

Fig. 2 is a plan view of the apparatus shown in Fig. 1 with the cover removed;

Fig. 3 is a vertical sectional view taken along the line III—III of Fig. 1;

Fig. 4 is an end elevation of the housing structure shown in Fig. 1; and

Fig. 5 is a detail view of the switch spindle and associated elements.

Referring now to the drawings more in detail, I show a switch stand having a housing 10, provided with a cover 11, which is secured in position by any suitable means, as by screws or bolts 12. A switch lever 13 is carried externally at one end of the housing and it is connected with a horizontal stem 14 movable with respect to a bearing 15 disposed within the housing.

A vertical spindle 16 has upper and lower bearing or trunnion portions 17 and 18, respectively, journaled in bearings 19 and 20 carried by the housing structure. Below the housing, a crank portion is provided by means of a threaded eyelet 21 which engages in the threaded opening 22 carried by the portion 18 below the housing. The upper portion 17 of the spindle may protrude above the cover 11 and have a target connected thereto in a manner well known in the art.

The lever 13 is arranged to swing in a vertical plane and it is adapted to move 180° in throwing the switch to either position, the lever 13 cooperating with suitable means, such as lugs 24 carried by the housing 10, in order that the lever may be locked in either of its horizontal positions. With movement of the lever 13 through an angle of 180°, the spindle 16 is moved through an angle of 90°; and I employ mechanism, at 25, for transmitting and transforming angular motion of the stem 14 into angular motion of the spindle 16, the latter moving through an angle of 90° for each 180° of movement of the stem 14.

Referring now more in detail to the mechanism at 25, it will be seen that the stem 14 carries a cross bar 26 at its forward end, the cross bar being provided with a forward bearing surface 27 which is inclined rearwardly and outwardly toward the ends of the bar from the central transverse plane thereof. A yoke 28 has yoke elements 29 adapted to overlap the bar 26 laterally and it is provided with a bearing element 30, such as a roller, for engagement with the bearing surface 27. The yoke 28 has a stem 31 connected thereto and the stem is journaled in a block 32 about an axis which is normal to the pivotal axis of the block with respect to the spindle 16, the spindle being provided with a central portion having side members

33 defining a slot to receive the block 32 and the members 33 having trunnion screws 34 having trunnion portions 35 adapted to fit lateral recesses in the block 32.

5 Lugs 37 are arranged at the ends of the bar for limiting motion of the yoke with respect thereto, such lugs or projections being provided with an inner surface which merges in a curved manner with the surface 27, and 10 lateral projections 37' of any suitable type are carried by the lugs 37 for coaction with the yoke portions 29 in order to limit outward movement of the yoke 28 with respect to the bar.

15 Whenever the stem 14 is moved angularly, the cross bar 26 moves angularly to the same extent. The yoke 28 moves with the cross bar and it is displaced both vertically and horizontally, the horizontal displacement 20 being transmitted to the spindle 16 while the vertical displacement is taken care of by swiveling motions of the stem with respect to the block and pivotal motions of the latter with respect to the spindle. It is characteristic 25 of the type of mechanical movement here utilized for transmitting motion from the stem to the spindle that the greatest mechanical advantage occurs at starting and ending of movements of the switch lever. 30 This is desirable for the reason that the maximum of resistance offered in the operation of the switch occurs when starting and when ending the switching operation.

Referring to the features of my construction 35 which give to the switch its spring character, it will be seen that the housing 10 is provided with a transverse wall 38 having its forward face 39 arranged adjacent to the rear face 40 of the cross bar 26. The wall 38 40 is provided with a recess 41 disposed horizontally and which is adapted to receive the cross bar 26 when the latter is in a horizontal position and is operated upon as hereinafter set forth.

45 At the bottom of the recess 41, the wall 38 is provided with openings 42 through which extend portions 43 of blocks 44, the latter having abutments 45 for limiting the blocks moving in the direction of the cross bar. Springs 50 46 are disposed between the blocks 44 and the end wall of the housing and serve to keep the blocks in position with the portions 43 extending through the openings 42 and through the recess 41, such portions 43 preferably 55 extending beyond the surface 39 so as to contact with the rear face of the cross bar when the latter is in a horizontal position.

The lever 13 has a slidable power-transmitting connection with respect to the stem 60 14, the lever preferably having a square opening 47 in its hub to receive a square end 48 of the stem 14.

From the structure described, it will be apparent that the stem 14 and its cross bar 26

are capable of rectilinear motion with respect to the housing whenever the cross bar is in a horizontal position when it registers with the recess 41; however, entrance movement of the cross bar into the recess is resisted by the springs 46 acting through the blocks 70 44. In this position of the cross bar, if power is applied to the spindle to turn the latter in such a direction as to move the yoke to the opposite end of the cross bar, such movement readily takes place for the reason that the 75 yoke presses the cross bar into the recess 41 compressing the springs 46; and, just as soon as the roller 30 passes beyond the highest portion of the bearing surface 27, the energy stored in the springs becomes effective to continue motion of the yoke until the latter reaches the other end of the bar. It will, therefore, be seen that my improved switch may be readily thrown in order to allow a train to pass therethrough. Owing to the 80 fact that the switch is yieldable only when the cross bar 26 is in registry with the recess 41, such cross bar being disposed adjacent to the upper surface 39 of the wall 38, my improved type of switch is positive for all positions of the stem 14 and cross bar 26 except the horizontal position of the latter. Positiveness is a valuable feature for the reason that should anything interfere with completion of movement of a spring rail with respect to a main rail, the lever 13 cannot be moved further to any substantial extent until whatever is causing the interference is removed or remedied. In this way, the switch 85 is comparatively fool proof for the reason that whenever the lever 13 is in a horizontal position this indicates that the switch has been correctly operated. This position is not only apparent to a switchman but also to others.

90 With the particular type of mechanism shown for transmitting motion from the stem 14 to the spindle 16, it is found that very little movement of the spindle 16 takes place during the beginning and final phases of 95 movement of the lever 13. For example, during the first 45° of movement of the lever 13 upwardly from a horizontal position, the spindle 16 moves only about 5°; during the 100 next 90° of movement of the lever 13, the spindle 16 moves substantially 80°; and during the final 45° of movement of the lever 13 to a horizontal position, the spindle 16 moves through about 5°. It will thus be seen that 105 the mechanism for transmitting motion from the stem 14 to the spindle 16 has adequate mechanical advantage at the beginning and at the completion of a switching movement, this being beneficial at the beginning in order to overcome friction and in the final phase 110 to secure a tight fit of a spring rail with respect to a main rail.

115 Should it be desired to make the switch

positive in all of its positions, this may be done either by restricting motion of the yoke 28 with respect to the cross bar, or rectilinear motion of the cross bar 26 and the stem 14 5 may be resisted positively in some manner. For example, I show the lever 13 having its hub portion confined between the end face 50 of the housing and a member 51, the hub portion being provided with an opening 52 10 adapted to register with an opening 53 in the stem 14. If, as shown in Fig. 3, a pin 54 is inserted in the registering openings 52 and 53, rectilinear motion of the stem 14 and its cross bar 26 is prevented and the switch 15 consequently becomes positive in all of its operative positions. If desired, the pin 54 may be made shearable, in which case a train 10 should run through the switch, the pin 54 would shear off avoiding either breakage of 20 the switch or derailment.

While I have shown my invention in but one form, it will be obvious to those skilled in the art that it is not so limited, but is susceptible of various other changes and modifications without departing from the spirit thereof, and I desire, therefore, that only such limitations shall be placed thereupon as are imposed by the prior art or as are specifically set forth in the appended claims.

Having thus described the invention what I claim as new and desire to secure by Letters Patent is:

1. In a spring and positive switch stand, the combination of a stem, a crank-carrying 35 spindle, means for transmitting rotary motion of the stem to the spindle and effective to transform rotary motion of the spindle, when the latter is the driving element, into rectilinear motion of the stem, and means for preventing rectilinear motion of the stem except when the latter occupies a predetermined 40 angular position.

2. In a spring and positive switch stand, the combination of a crank-carrying spindle, 45 a rotatable stem, mechanism for transmitting rotary motion of the stem to the spindle and for converting rotary motion of the spindle, when the latter is the driving element, into rectilinear motion of the stem, spring means 50 for resisting rectilinear motion of the stem, and means for preventing rectilinear motion of the stem except when the latter occupies predetermined angular positions.

3. In a spring and positive switch stand, 55 the combination of a housing, a crank-carrying spindle journaled in the housing, a stem journaled in the housing, a switch lever connected with the stem, mechanism for transmitting rotary motion of the stem to the 60 spindle and for converting rotary motion of the spindle, when the latter is the driving element, into rectilinear motion of the stem, projection means carried by the stem, abutment means carried by the housing and having a recess to receive the projection means

and serving to prevent rectilinear motion of the stem except when the projection means is in registry with the recess, and spring means for resisting rectilinear motion of the stem when the projection means is in registry with the recess. 70

4. In a switch stand, the combination of a housing, a vertical spindle journaled in the housing, a horizontal stem journaled in the housing, a switch actuating lever connected 75 with the outer end of the stem, a cross arm connected to the inner end of the stem, a block pivoted to the spindle about an axis normal to the spindle axis, and a yoke engaging the cross arm and having a stem 80 journaled with respect to the block about an axis normal to the pivotal axis of the latter, all of said axes intersecting at a common point.

5. In a switch stand, the combination of a 85 housing, a crank-carrying spindle journaled in the housing, a stem, a switch actuating lever connected with the outer end of the stem, a cross arm connected to the inner end of the stem and having a forward bearing surface, a block pivoted with respect to the spindle about an axis normal to the spindle axis, a yoke having a bearing element 90 cooperating with the bearing surface of the cross arm and having yoke elements disposed laterally of the cross arm, a stem connected to the yoke and journaled with respect to the block about an axis normal to the pivotal axis of the latter, all of said axes intersecting at a common point, and stop means carried 95 by the cross arm for limiting outward movement of the yoke with respect to the cross arm.

6. In a switch stand, the combination of a housing, a crank-carrying spindle journaled 105 in the housing, a stem journaled in the housing, a switch actuating lever connected with the outer end of the stem, a cross arm connected to the inner end of the stem, a wall carried by the housing and having a recess 110 adapted to register with the cross arm in predetermined angular positions of the latter, said cross arm having a forward bearing surface which is inclined rearwardly from a central transverse plane, a block pivotally connected to the spindle about an axis normal to the spindle axis, a yoke having a bearing element 115 engaging the bearing surface of the cross arm and having portions which overlap the cross arm laterally, a stem connected to the yoke and journaled in the block about an axis normal to the pivotal axis of the latter, all of said axes intersecting at a common point, stop means carried by the cross arm for limiting outward movement of the 120 yoke, and spring means for resisting entrance of the cross arm into said recess.

7. In a switch stand, the combination of a 125 housing, a crank-carrying spindle journaled in the housing, a stem journaled in the hous- 130

ing, a switch actuating lever connected with the outer end of the stem, a cross arm connected to the inner end of the stem, a wall carried by the housing, extending transversely of the axis of said stem, having a recess adapted to register with the cross arm in predetermined angular positions of the latter and having an abutment surface adapted to be disposed contiguously to the rear face of the cross arm in all positions of the latter except the registry position, said cross arm having a forward bearing surface which is inclined rearwardly from a central transverse plane, a block pivoted to the spindle about an axis normal to the spindle axis, a yoke having a bearing element engaging the bearing surface of the cross arm and having yoke portions which overlap the cross arm laterally, a stem connected to the yoke and journaled in the block about an axis normal to the pivotal axis of the latter, all of said axes intersecting at a common point, stop means carried by the cross arm for limiting outward movement of the yoke with respect thereto, and yieldable means for resisting entrance of the cross arm into said recess.

8. In a switch stand, the combination of a housing, a vertical crank-carrying spindle journaled in the housing, a horizontal stem journaled in the housing, a switch actuating lever having a slidable power-transmitting connection with respect to the outer end of the stem, a cross arm connected to the inner end of the stem, a wall carried by the housing and disposed transversely of the axis of the stem, said wall having a forward face disposed adjacent to the plane of the rear face of the cross arm and having a recess conforming to and adapted to register with the cross arm in predetermined angular positions of the latter, said cross arm having a forward bearing surface which is inclined rearwardly toward its ends from a central transverse plane, a block pivoted to the spindle about an axis normal to the spindle axis, a yoke having a bearing element engaging the forward bearing surface of the cross arm and having yoke portions which overlap the cross arm laterally, a stem connected to the yoke and journaled in the block about an axis normal to the pivotal axis of the latter, all of said axes intersecting at a common point, said wall having openings communicating with the recess, blocks extending through the openings and through the recess and adapted to engage the rear surface of the cross arm, abutment means carried by the blocks for limiting movement thereof toward the cross arm, and springs cooperating with the blocks to urge the latter toward the cross arm, whereby said springs serve to resist entrance movement of the cross arm into said recess.

9. In a switch stand, the combination of a housing, a vertical crank-carrying spindle

journaled in the housing, a horizontal stem journaled in the housing, a switch operating lever arranged externally of the housing and having a slidable power-transmitting connection with respect to the outer end of the stem, said lever being movable through substantially 180° in a vertical plane to substantially horizontal positions for operative settings of the switch, a cross arm connected to the inner end of the stem and having a forward bearing surface inclined from the central plane of the arm rearwardly towards the ends thereof, a wall carried by the housing and having one face thereof disposed closely adjacent to the plane of the rear face of the arm, said wall having a transversely recess adapted to receive the arm when the latter is in registry with the recess, a block pivotally connected to the spindle about an axis normal to the spindle axis, a yoke having a bearing element engaging with the bearing surface of the bar and having yoke elements arranged to overlap the bar laterally, a stem carried by the yoke and journaled about an axis disposed normally with respect to the pivotal axis of the block and passing through the point of intersection of the spindle axis and of the block pivotal axis, stop means arranged at the ends of the bar for limiting outward movement of the yoke with respect thereto, said walls having openings extending through the portion thereof at the bottom of said recess, blocks having portions extending through said openings and through the recess to bear against the rear face of the bar when the latter comes in contact therewith, abutment means carried by the last-named blocks for limiting motion thereof toward the bar, and spring means cooperating with the last-named blocks to resist entrance movement of the cross bar into said recess, said stem and said lever having registry openings for the reception of fastening means for resisting rectilinear motion of said stem in order that the switch may operate as one of the positive type for all positions thereof.

10. In a switch stand, the combination of a housing, a crank carrying spindle journaled in the housing, a switch actuating lever, a stem slidably mounted in said housing and slidably connected to said lever, a cross arm connected to the stem having a forward bearing surface which is inclined rearwardly in opposite directions from a central transverse plane, a member pivotally connected to the spindle and engaging the bearing surface of said cross arm, and resilient means constraining the latter into engagement with said member.

11. In a switch stand, the combination of a housing, a crank carrying spindle journaled in the housing, a switch actuating lever, a stem slidably mounted in said housing

and slidingly connected to said lever, a cross arm connected to the stem having a forward bearing surface which is inclined rearwardly in opposite directions from a central trans-

verse plane, a block member pivotally connected to the spindle, a yoke swivelled to said block member and straddling said cross arm,

a roller mounted in said yoke engaging said bearing surface, and resilient means urging said cross arm into engagement with said roller. 10

In testimony whereof I hereunto affix my signature this 22nd day of Jan., 1926.

JAMES M. HOFFER.
